Primary Examiner — Susan Bennett Hattan*Assistant Examiner* — Elizabeth S Ko(57) **CLAIM**

The ornamental design for a fixing device for windows and doors, as shown and described.

DESCRIPTION

FIG. 1 is a Perspective view of a fixing device for windows and doors showing my new design;

FIG. 2 is a Front elevational view thereof;

FIG. 3 is a Rear elevational view thereof;

FIG. 4 is a Right side view thereof;

FIG. 5 is a Left side view thereof;

FIG. 6 is a Bottom plan view thereof; and,

FIG. 7 is a Top plan view thereof.

The broken lines in the drawing depict portions of the fixing device for windows and doors that form no part of the claimed design.
